SKI POLE BASKET

Melville A. Miller, West County Line Road,
Barrington, Ill.

Filed Apr. 26, 1962, Ser. No. 69,865

Term of patent 14 years

(Cl. D34—14)

Fig. 1.

Fig. 2.

Fig. 3.

I claim:

The ornamental design for a ski pole basket, substantially as shown.
